UNITED STATES PATENT OFFICE.

EDMUND MORRIS, OF MICHIGAN CITY, INDIANA.

DESIGN FOR CANE FABRIC.

SPECIFICATION forming part of Design No. 26,859, dated March 30, 1897.

Application filed February 18, 1897. Serial No. 624,052. Term of patent 3½ years.

To all whom it may concern:

Be it known that I, EDMUND MORRIS, a citizen of the United States, residing in Michigan City, in the county of La Porte and State of Indiana, have invented and produced a new and original Design for Cane Fabric, of which the following is a specification, and which is illustrated in the accompanying drawing, showing a face view of a small piece of fabric with my design applied.

Cane fabric containing my design has alternate close-woven and open-mesh stripes A and B, the latter of which contain polygonal figures and star-shaped figures. Each stripe A is made up of a series of parallel strips a , arranged close together and divided up into short lengths or sections a' by a series of cross-strips a^2 . Each stripe B has a series of pairs of strips b , which form continu-

ations of the cross-strips a^2 and which, with the strips b' , running at right angles to them, and the diagonal strips b^2 , form a series of polygonal figures x . The diagonal strips b^2 are striped, cross each other, and form in the fabric a series of star-shaped figures y .

The leading feature of my design is the alternately-arranged close-woven and open-mesh stripes, the latter of which contain polygonal figures and star-shaped figures.

I claim—

The design for cane fabric, substantially as herein shown and described.

In testimony whereof I have hereunto subscribed my name.

EDMUND MORRIS.
